UNITED STATES PATENT OFFICE.

CHARLES J. VAN DEPOELE, OF CHICAGO, ILLINOIS.

CURRENT-REGULATOR FOR ELECTRIC MOTORS.

SPECIFICATION forming part of Letters Patent No. 291,650, dated January 8, 1884.

Application filed May 10, 1883. (No model.)

To all whom it may concern:

Be it known that I, CHARLES J. VAN DEPOELE, of Chicago, in the county of Cook and State of Illinois, have invented new and useful 5 Improvements in Current-Regulators for Electro-motors; and I do hereby declare that the following is a full, clear, and exact description thereof, reference being had to the accompanying drawings, which form a part of this 10 specification.

This invention relates to certain new and useful improvements in the construction of electric motors; and the invention consists in the peculiar construction of the different parts, 15 the mode of winding, and distributing the current in the electro-magnets and armature of said motor, as more fully hereinafter described.

The object of this improvement is to secure a perfect economical electric motor capable of 20 exerting its maximum force without materially lessening the speed of the motor or of doing its minimum duty without materially increasing said speed, and at the same time to take only as much current from the prime generator 25 as is used up in said motor, and proportionate to the amount of work exerted by the same.

Figure 1 is a diagram of connections through the whole system, with all the field-magnet coils in circuit. Fig. 2 is a vertical section 30 showing the disposition of the field-magnets with regard to the core of the armature. Fig. 3 is a front perspective elevation of my improved device. Fig. 4 is a detail plan view of the governor and connections. Fig. 5 is a 35 sectional elevation on line 5 5 of Fig. 3. Fig. 6 is a detail view on line 6 6 of Fig. 1, showing the commutator, its brushes and holders therefore, and the springs for pressing the brushes against the commutator, and also the adjacent 40 parts of the machine.

Similar letters denote like parts.

In the accompanying drawings, which form a part of this specification, A is the armature. B' and B'' are the polar extensions of the field-magnets M. C is the commutator. C' and C'' are the brushes. N is the negative and P the positive terminal of the circuits in the machine. P' P' P'' show the positive terminals of the coils M, and N' N' N'' show the negative terminals. As will be seen, the outside terminals P' of all the coils M are connected to one common conductor, P'', and all the inside terminals are connected to one common conductor, N'', when the bar N' is in contact with all the terminals n' n'', &c. 55

terminals are connected to one common conductor, N'', when the bar N' is in contact with all the terminals n' n'', &c. 55

In Fig. 1 the current enters by the pole P to the brush C', into the armature by corresponding sections of the commutator C, and out of the armature by the opposite section of the commutator to the brush C'' and terminal N. B' and B'' are the north and south pole-pieces or polar extensions of field-magnets M. E are the ends of the field-magnets, and E' and E'' are the top and bottom of the machine, all of cast-iron. The brushes C' and C'' and their 60 holders are carried by the circle H', and are movable around the commutator C by means of the handle H, from which they are suitably insulated. Said brushes are in electrical connection with the fixed semicircles K and L, 65 through the contact springs or brushes C' and C'', that are suitably secured to the handle H, and are permanently connected to the commutator-brushes C' and C''. By these means the current is taken from the fixed contacts 70 K and L, so as to enable the operator to stop and start the motor or reverse the motion of the same at will. The brushes and their 75 holders are placed diametrically opposite one another around the commutator, with the 80 brushes in a straight line to the center of the commutator. The holders in which the brushes are placed come very close to the commutator, and the brushes are pressed upon the same by suitable springs, R. By this arrangement I am enabled to reverse the motion 85 of the motor by moving the brushes to the right or left without changing their inclination with respect to the axis of rotation of the commutator as is necessary where the brushes are 90 placed in the usual way. G is a centrifugal 95 governor driven by a belt, g, passing over a pulley, g', and around pulleys on the armature-shaft and the shaft of the governor, and is driven by the same and regulates the speed 100 of the motor by raising or lowering the bar N' by means of a bar, h, extending from the movable sleeve of the governor, and thus placing a larger or smaller number of electro-magnet coils M in circuit, and thereby not only varying the number of magnet-poles acting upon the armature, but also, by varying the resistance of the circuit, controlling the amount of current passing through the armature. The

current in the armature can be reversed by moving the hand-lever H either to the right or left, thus placing the brushes C' and C' in contact with either one or the other of the semicircles K or L. This reverses the motion without reversing the current in the field-magnet coils.

The circuit in the machine is as follows: The current enters at P and passes by suitable connection over to the semicircle K, where it can be made to enter either the lower or the top brush of the armature. By turning the handle H to the right or left from P the current passes down to the terminals P', as shown in Fig. 1. By a suitable conductor, P'', the current is sent to the terminals P' on the right side of the machine. The current circulates through all the electro-magnet coils and comes out at the terminals N', which are led to the insulated posts n, (in Fig. 3,) placed upon a bar, W, made of wood or other suitable insulating material. From these posts the current passes by suitable contacts, n', to the bars N'', hinged to the standards S S'. The upper part of the standard S is insulated from the lower part of the standard, as shown, while the standard S' is the negative pole of the machine, the current leaving at N'', Fig. 3, and the circuit through the armature is completed by the conductor n'', which is in communication with semicircle L. F is a face-plate of wood or other suitable non-conducting material, carrying the plates K and L and the circle H'. On establishing the circuit with some proper source of electricity the current flows in multiple arc through the armature, and each independent electro or field magnet M, said armature and field magnets offering each a similar resistance thereto, and instantly the motor begins to revolve. Soon the armature and pulley and governor attain a speed which would go on increasing were it not for the governor G lifting up the bars N'' N'', which are hinged at S S', breaking contact with one or several of the contacts n', Fig. 3, until the speed of the armature corresponds to that for which the governor has been set.

When the motor has only a small amount of work to do, only one or two of the magnet-coils will be put in circuit, while the others will be cut out of circuit by the governor; but the moment the motor has a large amount of work to do the governor will slow down its speed and bring the bar down upon the contacts, and in so doing allow a larger or smaller number of electro-magnets to be put in action, until the speed of the armature again corresponds with the action of the governor. Any alteration in the speed of the motor will alter the number of coils or magnets in or out of circuit, and so regulate the speed and power of the motor.

This motor is specially designed to be used with a large number of similar motors in multiple arc from one generator or source of electricity. The potential of the generator is kept constant, and all the different electro-magnets

in the motors and also their armatures are wound with conductors of high resistance, the resistance in each individual field-magnet coil and in the coils of each armature being in all cases exactly the same, so that by keeping an even potential in the prime generator each circuit receives exactly the same amount of current, and so divides itself perfectly over any number of such circuits.

The motor can be made to run either back or forward without passing any current through the field-magnets by simply passing the current through the armature; but in the latter case the armature will revolve in the opposite direction from what it does when the field-circuits are closed, so that in case it is necessary to stop the motor it can be done by simply cutting off the current from the field-magnets, when the armature will tend to rotate in the opposite direction. When it has been brought to a standstill, it can be so kept by cutting off the current altogether by placing the handle and brushes in a vertical position.

What I claim as new is—

1. In an electric motor, the field-magnets composed of a number of independent electro-magnets not magnetically connected together at their poles or active ends, while their opposite ends are all connected magnetically to one common cast-iron plate, a similar system of electro-magnets being placed at each side of the revolving armature, the active ends of the electro-magnets facing each other, their opposite end plates secured to a cast-iron base and top, substantially as described.

2. In an electric motor, the combination, with independent and separate field-circuits, of a centrifugal governor adapted to bring a larger or smaller number of said field-circuits in operation, so as to regulate the speed and power of the motor, as described and set forth.

3. In an electric motor, a number of independent field electro-magnets, in combination with an armature, each field electro-magnet coil of the motor having the same resistance as the armature-coils, substantially as described.

4. An electric motor having a number of electro-magnet cores provided with pole-pieces facing each other on opposite sides of an armature-core, said armature and field-magnets having equally-resistant circuits around each of their cores, in combination with a source of electricity in which a constant potential is maintained to furnish current for said motor or motors, as described and set forth.

5. In an electric motor, and in combination with its revolving armature, a centrifugal governor receiving motion from said armature, and proper means connected to said governor to allow a larger or smaller number of electro-magnets to act upon the armature of the motor to regulate the power and speed of the same, substantially as described.

6. In an electric motor, a centrifugal governor driven by said motor, in combination with the bars N'' N'' and contacts n' n' n', &c., actuated by the centrifugal power of said gov-

ernor, in order to regulate the power and speed of the motor, by allowing a larger or smaller amount of current to act upon the revolving armature of the motor, substantially as described.

7. In an electric motor, a face-plate of wood or other suitable non-conducting substance or material provided with two semicircular plates of conducting material connected with the poles 10 P and N of a source of electricity, in combination with an oscillating hand-lever carrying brush-holders and brushes C' and C'', bearing upon the opposite side of a commutator so arranged and constructed that by the motion or 15 oscillation of the lever from right to left, or vice versa, the brushes bearing upon said commutator can be made to be in contact either with the positive or negative poles of the source of electricity, and so to be able to reverse the motion of said motor or to stop the 20 same when the brushes are placed between the opposite semicircular plates, as described, and for the purpose set forth.

8. In an electric motor, and in combination

with the commutator of the same, two brushes 25 placed diametrically opposite one another and in a straight line through the axis of rotation placed in a suitable holder coming very near the periphery of the revolving commutator, so as to be able to reverse the motion of the 30 armature by changing said brushes from right to left without altering their inclination with respect to the axis of rotation of the commutator, substantially as described.

9. In an electric motor, the brush-holders C' 35 and C'', placed diametrically opposite one another, and suitably secured to and insulated from the hand-lever H, and provided with contacts in the back of said hand-lever, so as to be able to place the opposite coils of the armature in circuit with the source of electricity necessary to run the motor by oscillating the handle H, so as to come in contact with the plates K and L.
